UNITED STATES PATENT OFFICE.

JACOB H. SCHEUER, OF NEW YORK, N. Y.

DESIGN FOR A TOILET-BRUSH.

43,182.

Specification for Design.

Patented Oct. 22, 1912.

Application filed August 21, 1912. Serial No. 716,335. Term of patent 14 years.

To all whom it may concern:

Be it known that I, JACOB H. SCHEUER, a citizen of the United States, residing in the city, county, and State of New York, have invented a new, original, and ornamental Design for Toilet-Brushes, of which the following is a specification, reference being had to the accompanying drawing, forming part hereof.

In the drawing, the figure represents a perspective view of the toilet brush showing my design.

I claim—

The ornamental design for a toilet brush as shown.

JACOB H. SCHEUER.

In the presence of—

F. WARNECK,
GEO. C. ROBERTS.
